(57) **CLAIM**

The ornamental design for a shadow ring lift pin, as shown and described.

DESCRIPTION

FIG. 1 is a front isometric top left-side view of a shadow ring lift pin.

FIG. 2 is a front isometric bottom left-side view thereof.

FIG. 3 is a left-side view thereof.

FIG. 4 is a front-side view thereof.

FIG. 5 is a right-side view thereof.

FIG. 6 is a back-side view thereof.

FIG. 7 is a top plan view thereof.

FIG. 8 is a bottom plan view thereof; and,

FIG. 9 is an enlarged partial view of the section 9 shown in FIG. 4.

The broken lines in the drawings illustrate portions of the shadow ring lift pin that form no part of the claimed design.

1 Claim, 4 Drawing Sheets
